UNITED STATES PATENT OFFICE.

EBEN N. GOWER, OF GAINESVILLE, GEORGIA.

REVERSIBLE FULCRUM FOR BRAKES.

1,258,557.

Specification of Letters Patent. Patented Mar. 5, 1918.

Application filed August 17, 1917. Serial No. 186,805.

To all whom it may concern:

Be it known that I, EBEN N. GOWER, a citizen of the United States, residing at Gainesville, in the county of Hall and State 5 of Georgia, have invented new and useful Improvements in Reversible Fulcrums for Brakes, of which the following is a specification.

This invention relates to a reversible fulcrum for brake beams, the primary object of 10 the invention being to provide a fulcrum or support for a brake beam, whereby the fulcrum member may be reversed, in a rapid, ready and convenient manner, for right or 15 left hand use, without the necessity of employing right and left hand brake beams or fulcrums.

A further object of the invention is to 20 provide a reversible fulcrum which is adapted to hold or lock the beam at the proper working angle in either of its positions of 25 adjustment, while permitting free pivotal motions thereof for braking actions, and which is adapted for use in connection with any ordinary type of brake beam, with or without trusses.

The invention consists of the features of 30 construction, combination and arrangement of parts hereinafter fully described and 35 claimed, reference being had to the accompanying drawing in which:—

Figure 1 is a top plan view showing the 35 application of the invention to one type of 40 brake beam, and illustrating in full and dotted lines the reversibility of the fulcrum member.

Fig. 2 is a side elevation of the same.

Fig. 3 is a vertical transverse section on line 3—3 of Fig. 1.

Fig. 4 is a vertical transverse section on line 4—4 of Fig. 1.

Fig. 5 is a longitudinal section through 45 the brake beam and transverse section through the lever engaging member of the fulcrum taken on the line of the fulcrum pin.

Fig. 6 is a perspective view of the lever engaging member detached.

Figs. 7 and 8 are similar views of the 50 sections of the beam carrying member detached.

Fig. 9 is a bottom plan view of the beam carrying member.

Fig. 10 is a similar view of a modified 55 form of lever engaging member.

Referring to the drawings, 1 designates a brake beam, of that type provided with a

V-shaped truss 2. 3 represents the brake lever, and 4 my improved reversible fulcrum or supporting bracket for pivotally connecting the brake lever with the brake beam. The beam shown is of the I-type, in 60 common use, and the invention is shown in the present instance as adapted therefor; although it is to be understood that the beam engaging member of the fulcrum bracket 65 may be of suitable type to engage any form of brake beam.

The reversible fulcrum and truss supporting bracket comprises, in addition to the lever engaging or fulcrum member 4, a beam carrying member 5. As shown, the beam carrying member 5 is composed of a head formed of a pair of semi-cylindrical sections 6 and 7, said sections being provided at one 70 end with angular jaws 9 to engage the base horizontal flange and the web of the beam 1, said jaws being perforated for the passage of a bolt 10 which also passes through the web of the beam, thus securing the beam carrying member in position. 75

The beam carrying member as thus constructed in sections is adapted for ready and convenient engagement with and disengagement from the brake beam, and, as shown, the semi-cylindrical sections 6 and 7 of the 80 head of this member are formed with coöperating sets of recesses 11, 12 and 13 best seen in Fig. 7. The recesses 11 are arranged at the outer end of the cylindrical head 5, while the recesses 12 are disposed between 85 the recesses 11 and 13, whereby the shoulders 14 and 15 are formed at the points of intersection of the respective recesses. The recesses 13 may, for convenience of construction, open into recesses 16 formed in the 90 jaws to receive the flanges of the brake beam, but this is not essential. The sections of the head 5 are provided with sets of diametrically disposed slots 17 and 18, arranged at right angles to each other, or at such other 95 angles as may be desired, and which open through the outer or lower end of the head 5, for a purpose hereinafter described.

The lever engaging or fulcrum member 4 comprises a block or substantially rectangular body having at one end a fulcrum pin 19 adapted to fit within the recesses 11 of the head 5, said pin being provided with a terminal annular flange 20 to fit within the recesses 13, and said pin being formed between its body portion and the flange 20 with a reduced portion or neck 21 to fit 100

within the recesses 12, the construction being such as to allow the fulcrum pin to have pivotal motion in the head 5 for rotation about its axis, and to form shoulders or stop surfaces 22 and 23 which hold the fulcrum pin from longitudinal motion in either direction.

The body and main portion of the fulcrum pin of the lever engaging member is 10 formed with a longitudinal slot 24 extending transversely therethrough for the passage of the fulcrum end of the lever 3, which is secured in position by a pivot pin 25 passing through openings in the sides of the 15 body of the engaging member and the lever, said pin being provided with a fastening 26, in the form of a cotter pin or key, for retaining it in position against displacement. The slots in the body portion and fulcrum 20 pin of the engaging member are adapted to permit the brake elements to have pivotal motion in service on the pivot pin as an axis, and the portions of this slot extending through the body of the fulcrum pin register with one or the other of the sets of 25 slots in the head 5 of the beam carrying member, and which are normally engaged by the lever, whereby a full working motion of the brake elements is permitted, while 30 the engagement of the lever with the slots in the head serves to lock the lever and the lever engaging member from pivotal motion on the fulcrum pin as an axis.

It will thus be understood that when the 35 lever is applied to the carrier member and engages one of the sets of slots, say the slots 17 in the beam engaging member, the beam and lever will be disposed at a proper relative working angle for right hand use and 40 will lock the parts of the fulcrum against relative pivotal motion, so that the parts will be maintained in such working position. By however disconnecting the pivot pin 25 and sliding the lever down into the bottom 45 of the slot 24 and out of engagement with the slots 17, the lever and its carrier member may be turned, as shown in dotted lines in Fig. 1, to dispose the beam and lever in a proper relative left hand working position, 50 and then upon sliding the lever into proper position in the slot 24 and reapplying the

pin 19 the lever will be brought into engagement with the set of slots 18, whereby the fulcrum members will be locked against displacement to retain the parts in the 55 working position mentioned.

It will thus be seen that the invention provides a fulcrum which will allow the lever to be turned to right or left for right or left hand use and will lock the lever in adjusted 60 position while allowing it to have free pivotal movement, and that the adjustment of the lever to either working position may be performed in a ready and convenient manner, whereby the use of right or left hand 65 fulcrums and beams will be avoided. The lever engaging member may be provided with a stem or projection 27 to receive a truss engaging member 28, comprising a tube having a notched end 29 to receive and 70 engage the truss, whereby the fulcrum may be suspended from the truss, as will be readily understood.

When the fulcrum is employed upon beams which are without trusses, a lever engaging or fulcrum member 4' of the form 75 shown in Fig. 10 may be employed, in which member the slot 24' may extend through the outer or lower end of the body of the member, thus obviously allowing the member to 80 be shortened and the lever to have free pivotal motion.

I claim:—

In a reversible fulcrum for brake beams, the combination of a beam engaging member 85 having a cylindrical head, provided with sets of diametrically disposed slots arranged at an angle to each other, a lever carrier member having a fulcrum pin journaled in said head for rotation to dispose said carrier member to support the brake lever in right or left hand working positions, the said carrier member being provided with a longitudinal slot, and a lever extending through and pivotally mounted in said slot, 90 said lever being movable in the slot for engagement with and disengagement from the slots in the head and adapted to interlock with one or the other of said sets of slots when in pivotally mounted position. 95

In testimony whereof I affix my signature.

E BEN N. GOWER.
